AIR COOLED CYLINDER FOR INTERNAL COMBUSTION ENGINES

Alex Freiherr von Seld, Jr., and Arnold Gumprecht, Hamburg, Germany

Application October 18, 1933, Serial No. 694,146

1 Claim. (Cl. 257—261)

The invention concerns an air cooled cylinder for internal combustion engines, consisting of a number of cooling-ribs each of which is subdivided into separate radially arranged teeth. The arrangements of this kind that have become known up to now in connection with stationary air-cooling-systems with artificial air-currents, all have the disadvantage that in their case the cooling air flowing past them does not find a system of channels which are connected with one another, and in which sufficient contact is established between the cooling air and the entire surface of the cooling ribs. Furthermore, the cooling air meets with too strong a resistance caused by the cooling ribs in the case of such a system. Other kinds of cooling ribs arranged in a circular manner round the cylinder, which are interrupted in parts and which offer resistance to the flow of air within the range of these interruptions show the same disadvantages, and moreover, it is difficult to construct them. Insufficient guidance for the cooling air between the cooling ribs has the result that the cylinder receives intense cooling only on the side opposed to the flow of air, whilst the opposite side of the cylinder is left to a space which has been subjected to rarefaction of air, which means that it receives practically as good as no flow of cooling air whatever. Owing to the manifold possibilities for the deflection of the current of air as for instance in the case of motorcycles such deflecting surfaces as the exhaust-pipes, the legs of the rider etc., or in the case of airplanes the strong whirling of air caused by the propeller, the cooling air is not always able to flow past the cooling ribs of the cylinder in one and the same direction. If no suitable channels are provided for the air to pass through in its flowing direction between the cooling-ribs, the air-cooling will not be sufficient. In so far as it is not possible in such a case to prevent the irregular cooling of the cylinder, there will be a danger of the cast-iron cylinder being distorted.

According to the invention, these disadvantages are remedied by the fact that the cooling-teeth have a rhombical cross-section and are tapered towards their free ends, the lateral surfaces of the teeth being arranged in the direction of two furrows of a screw which run in opposite directions to each other.

The drawing gives a working example of the object of the invention and shows:

Fig. 1 a cylinder of a combustion engine showing the new arrangement of cooling ribs, in an illustrative manner.

Fig. 2 a part of the outer casing of the cylinder unrolled.

Fig. 3 a vertical section on line 3—3 of Fig. 2.

Fig. 4 a row of cooling ribs seen from the side.

Fig. 5 a section through one of the ribs following the line 5—5 of Fig. 4.

In Fig. 1, "a" represents the cylinder of a combustion engine, which is fitted on its outer circumferential surface with cooling-ribs subdivided into a number of teeth and tapered towards their free ends. The lateral surfaces of the tooth-shaped cooling-ribs *b* are arranged in the direction of two furrows of a screw running in opposite directions to each other. The cylinder *a* can be constructed with its tooth-shaped cooling ribs as a metal casting in one piece. Besides, it is possible to construct the cylinder from a thick-walled hollow cylinder in such a manner that the channels provided for the flow of air passing in between the cooling ribs are milled or turned-out. For this purpose, first of all a right-handed, and then a left-handed screw-shaped groove is milled or turned into the cylinder casing. Thus, nearly trapeziform cooling-ribs with rhombical cross-section are produced. It is possible for the cooling air to flow round the cylinder, as well as to flow in a downward slanting direction through the right-handed screw-shaped groove, or in an upward slanting direction through the left-handed screw-shaped groove. The guide-channels provided in this manner for the cooling air, ensure intense cooling of the entire cylinder, the cooling effect bearing not only upon the part of the cylinder-wall facing the direction of the flow of air, but also upon the side of the cylinder that lies opposite to the direction of the flow of air, without rarefaction of air being caused in this space as this is usually the case otherwise.

Having now particularly described and ascertained the nature of our said invention, and in what manner the same is to be performed, we declare that what we claim is:—

A cooling system, especially adapted for cylinders of combustion engines with air-cooling, consisting of a cylinder having a number of cooling-ribs radially arranged and subdivided after the manner of teeth, which have a rhombical cross-section and are tapered towards their free ends, the lateral surfaces of the teeth of the cooling-ribs being arranged in the direction of two furrows of a screw crossing each other.
